UNITED STATES PATENT OFFICE

ERNEST DUNFORD, OF ST. LOUIS, MISSOURI, ASSIGNOR TO LANDIS MACHINE COMPANY, OF ST. LOUIS, MISSOURI, A CORPORATION OF MISSOURI

CHANNELING TOOL

Application filed February 16, 1931. Serial No. 516,260.

My invention relates to tools for use in repairing boots and shoes and consists particularly in a novel hand channeling tool. In certain processes in general use in the shoe making industry and in shoe repairing, it is desirable to cut a channel around the edge of the sole and insert stitches, for securing the sole to a welt or an upper, beneath the flap loosened by the channeling tool. 10 The flap is then cemented over the stitches and serves as a protection for the same.

Various hand channelers have been developed, but many of these have certain disadvantages which detract from the usefulness of the device. It has been found that in some of these tools there is insufficient guiding structure and hence there is a tendency for the knife to cut too deeply into the sole leather, while in others, wherein adequate guides are provided, the sole is distorted in passing over the knife so as to be pinched or cramped between the guides and the knife resulting in more difficult operation.

25 The main object of the present invention is to provide a channeling tool in which a knife will be satisfactorily guided through the sole leather in a plane constantly paralleling the upper surface of the sole and in which the leather will not be distorted and cramped between the guides and the knife. I attain this general object and other detail objects in the structure illustrated in the accompanying drawings in which

35 Figure 1 is a top view of my novel tool. Figure 2 is a side view of the same.

Figure 3 is an outer end view of the tool.

40 Figure 4 is a vertical transverse section taken on the line 4—4 of Figure 1 and showing a section through a leather sole being channelled.

45 The tool includes a handle 1 having a longitudinal recess 20 to receive a pin 2 of any suitable shape which projects rearwardly from the tool head 3. A rivet 4 extends transversely through the handle 1 and pin 2 holds the tool head and handle in assembled relation.

50 The tool head 3 is provided with a longitudinal cylindrical orifice 5 and is split longi-

tudinally at 12, forming ears 6 and 7. A screw 9 passes through ears 6 and 7 and serves as an adjusting means to vary the size of orifice 5 to permit the insertion and withdrawal of the shank of the knife 8. When assembled for use, knife 8 extends perpendicularly of the end of tool head 3. The knife blade is sharpened along edge 13 and has a sharpened leading point 14. The lower or bearing face 15 of the knife parallels the longitudinal axis of the tool head and is in line with the lower surface 16 of a trailing guide 10 projecting outwardly from head 3 and on the side thereof opposite ears 6 and 7.

55 Knife 8 and guide 10 preferably contact at their adjacent edges and their lower sides co-operate to form a continuous plane bearing surface. The outer ends of knife 8 and guide 10 are beveled away from their respective leading points and lower surfaces as shown at 17 and 18 in Figure 1.

60 A leading guide 11 projects forwardly from ear 6 and is disposed above the lower or bearing surface of knife 8 by a distance equal to the desired thickness of the flap to be raised from the sole. The edge 19 of guide 11 engages the sole, preventing the knife from cutting too deeply into the work, and the lower surface of guide 11 is somewhat inclined to the plane of the bearing face of 65 the knife to facilitate the passage of the guide over the upper surface of the leather.

65 In Figure 4 I show my improved tool being used to channel a sole S. It will be noted that the knife blade is held on a straight course through the leather by guides 10 and 11 positioned in front and in back of the knife, respectively, guide 10 preventing the knife from cutting out through the top of the flap F and guide 11 preventing the knife 70 from cutting too deeply into the leather S. However, the portion of the sole being channelled is not cramped by being corrugated over the knife and under the front and rear guides so that there can be no pinching or 75 cramping to unduly resist the passage of the knife.

80 Obviously, the guides and other parts shown in the selected embodiment may be modified to a certain extent as to shape and 85

size and other details, and any suitable type of knife may be substituted without departing from the spirit of my invention and I contemplate the exclusive use of all such variations as come within the scope of my claims.

I claim:

1. A hand channeling tool including a knife member having a flat face with a cutting edge, and a guide member having a guide surface in the plane of the face and edge of said knife member and at the side of said knife member opposite to said cutting edge to control the relative inclination of the knife and the work as they move past each other.
- 15 2. A channeling tool including a handle, a head portion, a knife, and a trailing guide protruding from said portion, said guide being positioned to follow said knife through the channel being cut, and to co-operate with said channel to prevent rotation to the tool relative to said channel.
- 25 3. In a channeling tool, a knife having a cutting edge and a shank portion, a head releasably gripping said shank portion, a guide member projecting from said head and having a plane guiding surface in line with the cutting edge of said knife, and a second guide having the lower surface thereof spaced above the plane of said edge and said first mentioned surface and adapted to slide along the top of a sole being channeled.
- 35 4. In a channeling tool, a guide, a knife in a plane spaced below said guide and having a cutting edge adjacent said guide, and a second guide on the side of said knife opposite said first mentioned guide and having a guiding surface in said plane.
- 40 5. In a channeling tool, a knife, a trailing guide adjacent said knife and having a guiding surface in the same plane therewith, and a leading guide having a guiding surface spaced above said plane and adapted to slide along the top of a sole being channeled, said second mentioned guiding surface having an upwardly inclined forward portion.
- 45 6. In a channeling tool, a knife having a plane bearing face in line with the cutting edge thereof and an upper surface inclined upwardly from said edge and plane, and a trailing guide having a guiding surface forming a continuation of the bearing face of said knife and having an upper surface inclined in the same general direction as the upper surface of said knife, the outer ends of said knife and said guide being inclined rearwardly and inwardly from their respective leading points and lower surfaces.
- 50 7. In a channeling tool, a knife, a leading guide having a guide surface disposed to bear against the top of a sole being channeled, and a trailing guide arranged to move within the channel, the portion of said tool above said trailing guide being open to permit the free passage away from the knife of the loosened flap.

8. In a tool for channeling the edge of sole leather, a knife, a front guide member in front of said knife and a rear guide member at the rear of said knife, said front guide member being above the plane of said knife, to engage the top face of the leather, and said rear guide member being in the plane of said knife, to engage the bottom face of the channel, and being relatively thin to permit the flap of the channel to ride over it readily.

In testimony whereof I hereunto affix my signature this 9th day of February, 1931.

ERNEST DUNFORD.
